VALVE GRINDING DEVICE

N. C. Woods, Rayville, La.

Application April 15, 1940, Serial No. 329,818

1 Claim. (Cl. 251—37)

My invention relates to valves and more particularly to valves of the self-grinding type.

One of the principal objects of my invention is to provide a novel and improved means for association with a valve to effect a grinding of the valve seat by the grind member.

Another object of my invention is to provide an improved means or device of the above described character which is simple in construction, durable in use, efficient in operation and economical in manufacture.

A special object of my invention is to provide a device so constructed and arranged whereby the same may be attached to valves already in use without modifying the same.

Other objects and advantages will be apparent from the following description, appended claim and annexed drawing.

Referring to the drawing wherein like reference characters designate like parts throughout the several views:

Figure 1 is a vertical sectional view of a valve and illustrating my invention as applied thereto.

Figure 2 is a side elevation of the valve and illustrating my invention as attached thereto in operative position.

In practicing my invention, as illustrated in the drawing, I provide a valve casing 9 of ordinary construction and which is provided with a web 10 formed with a valve seat 11. The casing 9 is provided with an upper section 12 having a chamber 13 superjacent the valve seat 11 and which is normally closed by a bonnet 14 having its lower end 15 threaded therein as illustrated in Figure 2 of the drawing.

The bonnet 14 is provided with a centrally disposed and axially extending bore 16, the lower end of which is threaded as at 17 for threaded engagement with threads 18 formed on the lower end section of a valve stem 19 rotatably mounted within the bore. The upper end of the bonnet 14 is externally threaded and receives thereon a cap 20 sleeved over the stem 19 to maintain a packing gland 21 disposed about the stem in sealed relation with the latter to preclude leakage of fluid from within the valve casing.

The lower end of the valve stem 19 is provided with an inverted frustum-shaped valve member 22 for seating engagement with the valve seat 11. The upper end of the valve stem 19 is provided with a hand wheel 23 for operating the valve stem 19 to raise and lower the valve member 22 with respect to the valve seat 11 to open and close the passage therein between the aligned inlet and outlet openings 24 of the casing 9.

The lower bottom wall of the casing 9 is formed with a subjacent eyed ear 25 through which is disposed one end of an S hook 26. The opposite end of the hook 26 is detachably connected to an eyed ear 27 exteriorly formed on a valve grinding attachment or means 28.

The valve grinding attachment comprises a hollow member or sleeve having upper and lower sections 29 and 30 respectively with the upper section of a greater diameter than the lower section. The lower section is exteriorly threaded as at 31 for threaded attachment within the upper section 13 of the valve casing while the upper section is interiorly threaded for threadedly receiving therein the lower end section of the bonnet 14 as clearly illustrated in Figure 1 of the drawing.

In use (the threaded portion of the valve stem 19 being disposed within and in threaded engagement with the threads 17 of the bonnet 14), the bonnet 14 is detached from the section 13 of the casing 9 and the lower section 30 of the sleeve 28 threaded into the section 13 whereupon the lower end section of the bonnet is threaded into the upper section 29 of said sleeve. When the parts are thus assembled the valve stem 19 is rotated to dispose the threads 18 out of engagement with the threads 17 and subjacent the lower end of the bonnet.

Obviously, when the parts are thus arranged (with the valve member 22 having seating engagement with the valve seat 11) downward pressure is applied to the valve stem 19 and the latter rotated or oscillated to effect a grinding of the valve seat 11 by the valve member 22. When the valve seat 11 has been sufficiently ground the sleeve 28 is detached from the section 13 and bonnet 14 and connected to the hook 26 for further use, while the valve stem 19 is threaded upwardly into the bonnet and the latter threadededly connected to the section 13 to permit functioning of the valve in the ordinary manner.

From the foregoing it will be apparent that I have provided a hollow member or sleeve which is adapted to be inserted between the casing and bonnet of a valve for spacing the bonnet a sufficient distance away from the valve seat to permit the valve stem to be disposed downwardly out of threaded engagement with the bonnet and with the valve member engaging the valve seat whereby to permit grinding of the valve seat by the valve member when the valve stem is oscillated or rotated. If desired, the upper section of the sleeve 28 may be polygonally faced to receive the jaws of a wrench or the like to effect at-

tachment or detachment of the sleeve to and from the upper section 13 and the bonnet.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and sub-combinations.

It is obvious that the invention is not confined to the herein described use therefor as it may be utilized for any purpose to which it is adaptable. It is therefore to be understood that the invention is not limited to the specific construction as illustrated and described, as the same is only illustrative of the principles of operation, which are capable of extended application in various forms, and that the invention comprehends all construction within the scope of the appended claim.

What I claim is:

In a valve, the combination with a valve body

having a seat therein and an interiorly threaded bonnet engaging neck section, a bonnet having an exteriorly threaded inner portion engageable with the body neck and provided with an interiorly threaded bore, a valve stem extended through the bore of the bonnet having a threaded section at its inner end normally engageable with the threads of the bonnet for axially moving the stem upon rotation thereof, and a valve on the 10 inner end of the stem engageable with the said valve seat, of a tubular member exteriorly threaded at one end for detachable engagement with the neck section of the body and interiorly threaded at its opposite end for engagement with the threaded portion of the bonnet, the said tubular member being adapted to firmly unite the bonnet and body in spaced apart relation so that the threaded portion of the stem will be disengaged from the bonnet when the valve is seated whereby the stem may be rotated without axial movement for grinding the valve seat.

N. C. WOODS.
